(57) **CLAIM**

The ornamental design for a knee massaging device, as shown and described.

DESCRIPTION

FIG. 1 is an elevated perspective view of a knee massaging device, showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines in the drawing depict portions of the knee massaging device and form no part of the claimed design.
